(72) **Inventors:** **Nayda Aponte**, Northampton, PA (US);
Karelys Alfonzo, Coopersburg, PA
(US); **Advait Tinaikar**, Bethlehem, PA
(US); **Brad Michael Kreschollek**,
Bethlehem, PA (US); **Edward Wunsch**,
Quakertown, PA (US); **Somesh Rahul**,
Breinigsville, PA (US); **Sanjeev
Kumar**, Harleysville, PA (US)

(73) **Assignee:** **Lutron Technology Company LLC**,
Coopersburg, PA (US)

(**) **Term:** **15 Years**

(21) **Appl. No.:** **29/984,286**

(22) **Filed:** **Jan. 14, 2025**

OTHER PUBLICATIONS

Crestron Electronics Inc., Crestron Mobile E-Control Mobility
Solution, available at least as early as Mar. 2009.

(Continued)

(53) Continuation of application No. 29/896,129, filed on
Jun. 29, 2023, now Pat. No. Des. 1,070,883, which is
a continuation of application No. 29/817,959, filed on
Dec. 6, 2021, now Pat. No. Des. 993,972, which is a
continuation of application No. 29/767,277, filed on
Jan. 21, 2021, now Pat. No. Des. 940,160, which is a
continuation of application No. 29/704,241, filed on
Sep. 3, 2019, now Pat. No. Des. 909,402.

Group, LLC

(57) **CLAIM**

The ornamental design for a display screen or portion
thereof with graphical user interface as shown and
described.

DESCRIPTION

The sole FIGURE shows a display screen or portion thereof
with graphical user interface showing our new design.
The peripheral dashed broken lines illustrate a display
screen or portion thereof, and form no part of the claimed
design.

1 Claim, 1 Drawing Sheet
